(57) **CLAIM**

The ornamental design for a graphic user interface for a display panel, as shown and described.

DESCRIPTION

FIG. 1 is a front view of a first embodiment of a graphic user interface for a display panel showing our new design;

FIG. 2 is a front view of a second embodiment of the graphic user interface for the display panel showing our new design; and,

FIG. 3 is a front view of a third embodiment of the graphic user interface for the display panel showing our new design. The broken line portions of the drawings are for illustrative purpose only and form no part of the claimed design.
